US00D842456S

(12) **United States Design Patent** (10) **Patent No.:** **US D842,456 S**
Miller et al. (45) **Date of Patent:** **** Mar. 5, 2019**

(54) **AIRWAY DEVICE**

- (71) Applicants: **INTERSURGICAL AG**, Vaduz (LI);
Muhammed Aslam Nasir, Caddington,
Bedfordshire (GB)
- (72) Inventors: **Andrew Neil Miller**, Crowthorne (GB);
Jane Elizabeth Kemp, Bristol (GB);
Muhammed Aslam Nasir, Caddington
(GB)
- (73) Assignees: **INTERSURGICAL AG** (LI);
Muhammed Aslam Nasir (GB)

(**) Term: **15 Years**(21) Appl. No.: **29/548,655**(22) Filed: **Dec. 15, 2015**(51) LOC (11) Cl. **29-02**

(52) U.S. Cl.

USPC **D24/110.5**

Primary Examiner — Karen E Kearney*Assistant Examiner* — Lilyana Bekic(74) *Attorney, Agent, or Firm* — Hayes Soloway P.C.(57) **CLAIM**

The ornamental design for an airway device, as shown and described.

DESCRIPTION

FIG. 1 is a top perspective view of an airway device showing our new design;

FIG. 2 is a bottom perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front perspective view thereof; and,

FIG. 8 is a rear perspective view thereof.
